11 Claims. (Cl. 19—105)

This invention relates to improvements in carding machines.

Heretofore, in the conventional carding machine the material fibers fed from the feed roller were taken by the licker-in and separated of their short fibers and foreign matters contained therein such as dust, pieces of seed, etc. by means of the centrifugal force induced by the rotation of the licker-in and by gravity, following which the short fibers and foreign matters by falling to the bottom were removed. On the other hand, the spinnable fibers, i.e. the long fibers, carried on the licker-in were taken by the wire-clothing surface of the carding cylinder which rotates contiguously to said licker-in, and thus were carded.

However, since in such a carding machine the mechanism of the licker-in part was of a construction in which the emphasis was on its action in opening the fibers fed from the feed roller and in preventing the long fibers from falling out, although the loss of the long fibers was small, there was the tendency to prevent the falling out of the foreign matters even at a sacrifice of a part of the cleaning action of the foreign matters. Therefore, the foreign matters without having been completely removed remain on the licker-in and are transferred to the carding cylinder where they increase the carding load between the wire-cloth or the saw tooth wire of the carding cylinder and the wire-cloth or the saw tooth wire of the revolving flats as to lower the carding effects as well as to hinder the drafting operation of the operations that succeed on account of the foreign matters that will still remain in the slivers. Thus the lowering in the quality of the product was unavoidable.

A primary object of the present invention is to provide a carding machine in which the speed at which the licker-in rotates can be raised so as to enhance the opening capacity without however the attendance of a loss in the long fibers.

Another object of the invention is to provide a carding machine in which is installed below the carding cylinder at a point close to the licker-in a means which, during the opening operations, not only removes from within the fibers the lighter foreign matters but also at the same time recovers the spinnable fibers; and also in which the heavier foreign matters can be separated and removed by centrifugal force and gravity.

The carding machine of the present invention is made up as follows: It consists of a feed table and a feed roller disposed thereabove for feeding the material fibers, at least one licker-in provided adjacent the feed table and a carding cylinder disposed on the opposite side from the feed table with the periphery of said licker-in and that of the carding cylinder being adjacent to each other. An upper casing covers the upper part of the licker-in as well as a part of the upper part of the adjacently disposed carding cylinder, while below the licker-in there is provided an air chamber enclosed with four walls and having an air inlet in the wall next to the feed table. And below the carding cylinder at a point close to the licker-in there is provided a perforated cylinder positioned as to be capable of rotation in contiguity to the carding cylinder but spaced with an interval from said licker-in. Within the perforated cylinder is provided a suction compartment whose

2

opening is directed to open towards a place at least other than that where said perforated cylinder and the carding cylinder come adjacent to each other. And the position of the perforated cylinder relative to the air chamber is such that at least air can be drawn thereinto.

Therefore, when the carding machine of the present invention is operated the relatively heavier components of the foreign matters contained in the fed material fibers are removed as they break through the layer of air stream flowing below the licker-in by means of the centrifugal force induced by the rotation of the licker-in and by gravity and fall to the bottom. On the other hand, the components consisting of such as the opened fibers and the relatively lighter foreign matters, for example, minute dusts, etc. float in said air stream and being conveyed thereby are drawn to the opening of the suction compartment of the perforated cylinder provided below the carding cylinder in a position nearer to the licker-in. Here, the long fibers are caught on the periphery of the perforated cylinder while the minute dusts and short fibers, being drawn into the suction compartment, are exhausted by a suction means.

For a better understanding of the invention, it will be described with reference to the accompanying drawings, in which:

FIG. 1 is a sectional view of the essential parts of an embodiment of the present invention;

FIG. 2 is a sectional view taken on line II—II of FIG. 1;

FIGS. 3 to 10 are sectional views each illustrating other embodiments of the invention. In the drawings, like reference characters refer to like parts.

The carding machine of the present invention shown in FIG. 1, as is the case with the known carding machines, has a licker-in 3 disposed contiguously to a feed table 1 to which top is mounted a feed roller 2. And at the side of the licker-in 3 opposite from said feed table 1 there is provided a carding cylinder 4 disposed so that it rotates with its periphery in contiguity to that of the licker-in. Above the carding cylinder 4 whose periphery is clothed with a saw tooth wire or a wire-cloth 4a there are usually provided revolving flats (not shown) whose peripheries are similarly clothed with wire-cloths or saw tooth wires, and the carding cylinder 4 and the revolving flats are so disposed with respect to each other that they rotate in contiguity to each other.

As shown in FIG. 1, the licker-in 3 of the carding machine of the present invention has the whole of its periphery clothed with a saw tooth wire 3a, and an upper casing 5 covers the upper part of the licker-in 3 as well as a part of the carding cylinder 4 adjacent thereto. And the licker-in 3 at least at its underside faces an air chamber 6 which, except that it has an opening 7 for the inflow of air in its front wall 6a i.e., the wall nearest to the feed table 1, and that the upper part of its rear wall 6b is incised as to allow a rotatable perforated cylinder 8 to face towards the inside of the air chamber 6, is substantially closed from the outside by being enclosed with four walls.

The perforated cylinder 8 is provided below the carding cylinder 4 near the licker-in 3 and is so positioned that although it is spaced with an interval from the licker-in 3, it is capable of rotating while in contiguity to the carding cylinder 4. And, as already described, at least a part of it, excepting that part adjacent the carding cylinder 4, faces towards the inside of the air chamber 6. Within this rotatable perforated cylinder 8 there is provided a suction compartment 9, an opening 9a of which opens towards that part where the perforated cylinder 8 faces towards the inside of the air chamber 6. Although not shown in the figure, the suction compartment is connected with a suitable suction means by which the

air inside the suction compartment 9 is exhausted to the outside. The suction compartment 9 moreover opens adjacent the inner periphery of the perforated cylinder, extending across the entire width thereof.

FIG. 2 illustrates an example of a suction mechanism of the perforated cylinder 8 of FIG. 1 and a mechanism for adjusting the position at which the opening 9a of the suction compartment 9 opens.

In FIG. 2 the two ends of the perforated cylinder 8 are journaled in the frame 20, 20 by means of ball bearings 21, 21, and a pulley 22 is secured to one of the ends thereof. By driving this pulley 22 with a belt the perforated cylinder 8 is rotated. The ends of the suction compartment 9 are journaled in the ends of the perforated cylinder 8. At one end of the suction compartment 9 that protrudes a little from the end of the perforated cylinder 8 a handle 23 is secured. By means of this handle 23 the suction compartment 9 can be turned through a small angle. A stud 25 secured to the handle 23 extends slidably through a curved slot 24 provided in a plate 27 that is secured to the frame. By tightening a nut 26 that is threaded to the stud 25 the handle 23 can be fixed at an optional position within the limits of the slot 24. Hence, even though the perforated cylinder rotates, the suction compartment does not rotate but remains stationary.

When the carding machine illustrated in FIGS. 1 and 2 is operated, the material fibers that have been fed from between the feed table 1 and the feed roller 2 are immediately taken by the saw tooth wire 3a of the licker-in 3 as to result in a greater part of the spinnable fibers being transferred to the saw tooth wire 4a of the carding cylinder 4 while in a state as caught on said saw tooth wire 3a, but, on the other hand, the foreign matters and the short fibers as well as a part of the spinnable fibers which are present within the material fibers leave the periphery of the licker-in 3 and fall out. However, in case of the carding machine of this invention, since on account of the suction action of suction means that is connected to the suction compartment 9 within the perforated cylinder 8 an air stream is set up in the air chamber 6 below the licker-in 3 flowing in from an opening 7 of the front wall 6a of said air chamber 6 and along the underside of the licker-in 3 to be drawn into the suction compartment 9 within the perforated cylinder 8, only the relatively heavier foreign matters break through the air stream and drop to the bottom of the air chamber 6, whereas the relatively light foreign matters and the short fibers as well as the spinnable fibers, while floating in the air stream, arrive at the suction part of the perforated cylinder 8. Here, the minute foreign matters and the short fibers by passing through the numerous perforations 8a of said perforated cylinder 8 are exhausted to the outside of the machine by the suction means. On the other hand, the spinnable fibers whose fiber length is relatively long get caught on the periphery of the perforated cylinder 8 from which as a result of the rotation of the perforated cylinder 8 they are then taken off by the saw tooth wire 4a of the carding cylinder 4 where, after being combined with the spinnable fibers that have been directly transferred from the licker-in 3, as already described hereinbefore, they are carded.

As described hereinabove, the cleaning efficiency of the carding machine of the invention that is shown in FIG. 1 is very excellent. Accordingly, since the speed at which the licker-in 3 and the carding cylinder 4 rotate can be increased commensurately, the carding capacity increases, and moreover, a loss in the spinnable fibers is small.

The embodiment illustrated in FIG. 3 is identical to that of the hereinabove-described carding machine as shown in FIG. 1, except for the fact that a mote-knife 30 is disposed under the licker-in 3 spaced from the periphery thereof with an interval sufficient for the passage of the fibers.

According to the embodiment of FIG. 3, as the mote-knife 30 is disposed under the licker-in 3, the air stream containing the foreign matters and short fibers as well as spinnable fibers is deflected downwards abruptly as to make possible the removal of the relatively heavier foreign matters much more effectively than in the instance of the embodiment shown in FIG. 1.

The cleaning efficiency at the underside of the licker-in 3 is naturally related to such as the intensity and thickness of the air stream layer, and it is preferred that adjustments be made of the intensity of the air stream and its thickness in accordance with the types and proportions of foreign matters contained in the material fibers. For this purpose, it is advantageous to provide a damper (not shown) in the opening 7 of the front wall 6a of the air chamber 6, or to provide for the regulation of the suction force of the suction means, or also make it possible to vary the shape, size, etc. of the mote-knife 30.

FIG. 4 illustrates a carding machine that differs still further from the hereinbefore-described embodiments.

In this embodiment the rear wall 6b of the air chamber 6 is disposed somewhat more to the front than in the case of that shown in FIGS. 1 and 3. In this instance, the upper part of the rear wall 6b forms an under casing 40 that covers the underside of the licker-in 3 spaced with an interval therefrom. The underside of the carding cylinder 4 at that part below where it and the licker-in 3 come adjacent to each other is also covered with an under casing 41 that is spaced with a small interval from said carding cylinder 4.

In a part of the under casing 40 of the licker-in 3 a duct 42 opens up, the other end of which duct 42 opens towards the periphery of the perforated cylinder 8. Opposite this latter opening and opening towards the inner periphery of the perforated cylinder 8 the opening 9a of the suction compartment 9 is positioned. In the embodiment shown in FIG. 4 the construction is such that the air inside the suction compartment 9 is drawn by means of an exhaust fan 45 via a duct 44.

When the carding machine shown in FIG. 4 is operated, the air that enters from the opening 7 in the front wall 6a of the air chamber 6 flows along the underside of the licker-in 3, and after passing between the underside of the licker-in 3 and the under casing 40, and thence through the duct 42 as well as the numerous perforations 8a of the perforated cylinder 8 enters the suction compartment 9, following which it is exhausted to the outside in consequence of the operation of the exhaust fan 45. The operation in this instance is substantially the same as described in connection with the embodiment shown in FIG. 1.

However, in the carding machine of FIG. 4, by adjusting such as the length that the joint portion 40' projects into the air chamber 6 and the extent of the bow therebelow as well as the angle that the tip of the undercasing 40 opens with respect to the licker-in 3 it becomes possible to regulate such as the deflection and convergence behaviors of the air stream forward of said joint portion 40' and the intensity of the air stream depending on the various conditions such as the types and proportions of the foreign matters contained in the material fibers, etc. Moreover, in the embodiment shown in FIG. 4, since there is provided a saw tooth wire 43 on the outer periphery of the perforated cylinder 8, the spinnable fibers get caught on the saw tooth wire 43; thus not only is there no possibility that the perforations 8a would become clogged, but also the transfer of the spinnable fibers to the carding cylinder 4 is effected smoothly.

The carding machine of the invention illustrated in FIG. 5 is of a construction completely identical to that shown in FIG. 4, except that a mote-knife 30 is provided below the licker-in 3 as in the instance of that shown in FIG. 3, and further a damper 50 is provided in the side wall of the duct 42.

This carding machine has, besides the advantages of the carding machine of FIG. 4, the advantages not only that

its cleaning efficiency becomes still greater, because the air that has entered from the opening 7 of the front wall 6a is deflected at two places in the air chamber 6, i.e., at the mote-knife 30 and at a point forward of the joint portion 40'; but also that the intensity of the air stream flowing along the underside of the licker-in 3 can be regulated by operating the damper 50 provided in a side wall of the duct 42.

In the embodiment shown in FIG. 6, a hinged plate 60 which constitutes a part of the under casing of the licker-in 3 is hinged to the rim portion 61 of the opening of the duct 42. And to this hinged plate 60 there is attached a sliding plate 62 of angular section as to be slidable with respect to said hinged plate 60 by suitable means such as, for example, a stud with a winged nut 63. Further, to the bottom of the sliding plate 62 an elastic sheet 64 such as, for example, a rubber or a synthetic resin sheet, is so attached that its bottom edge reaches the floor of the air chamber 6. Thus, by means of the lower part 62b of the sliding plate 62 and the elastic sheet 64 the rear wall of the air chamber 6 is constituted. And to the lower part 62b of the sliding plate 62 is secured a projecting piece 65 to a part of which is attached a lever 66 that is pivoted by a pin 67.

Therefore, when the lever 66 is turned, the sliding plate 62 either rises or falls, and with the rim portion 61 of the duct 42 as the pivot the fore part of the under casing which is constituted by combining the sliding plate 62 and the upper part 62a of the sliding plate 62 turns thereby adjusting the angle of spread of this under casing with respect to the underside of the licker-in 3. In addition, by manipulation of the winged nut 63 the length that the sliding plate 62 projects beyond the hinged plate 60 is adjusted.

Thus, in the carding machine shown in FIG. 6, it is possible to adjust the under casing constituted of the hinged plate 60 and upper part 62a of the sliding plate 62 as to the angle that it makes with respect to the underside of the licker-in 3 as well as its length. By effecting these adjustments not only can an air stream of optimum intensity be set up below the licker-in 3 depending upon such as the types and proportions of the foreign matters as well as the rate at which short fibers are contained in the material fibers, but the angle of deflection of the air stream forward of the projecting end 62c of the sliding plate 62 can also be controlled for achieving optimum cleaning efficiency.

In the embodiment shown in FIG. 7, the underside of the licker-in 3 at a part thereof nearer to the carding cylinder 4 is covered with an under casing 71 spaced with a slight interval from the periphery of said licker-in 3, the tip of the under casing 71 being connected to a mote-knife 72. And still further below said under casing 71 and in contiguity to the carding cylinder 4 there is provided the perforated cylinder 8. The underside of the carding cylinder 4 at that part nearer to the licker-in 3, excepting the part where the perforated cylinder 8 comes adjacent thereto, is covered with an under casing 73 spaced therefrom with a slight interval.

As in the case of the various embodiments described hereinbefore, the perforated cylinder 8 is provided within it a suction compartment 9 which opens toward a suitable direction other than where said perforated cylinder 8 and the carding cylinder 4 come adjacent to each other.

Hence, when the carding machine illustrated in FIG. 7 is operated, the material fibers that are fed from between the feed table 1 and the feed roller 2 are immediately taken by the saw tooth wire 3a of the licker-in 3, and a greater part of the spinnable fibers in the state as caught on the saw tooth wire 3a are transferred to the carding cylinder 4. On the other hand, the foreign matter, short fibers as well as a part of the spinnable fibers which fall out as a result of the raking off action of the saw tooth wire 3a float in the air stream flowing in from the opening 7 of the front wall 6a, and after first being deflected at

the mote-knife 72 proceed towards the perforated cylinder 8. Hence, during this time the relatively heavier foreign matter fall out to the floor of the air chamber 6 chiefly when the air stream is deflected at the mote-knife 72.

On the other hand, the minute foreign matter and short fibers pass through the perforations 8a of the perforated cylinder 8 and enter the suction compartment 9, following which they are exhausted to the outside of the machine. However the spinnable fibers get caught on the perforated cylinder 8 and due to its rotation are then taken by the saw tooth wire 4a of the carding cylinder 4 where they are carded after having been combined with the spinnable fibers that have been transferred to the carding cylinder 4 directly from the licker-in 3.

FIGS. 8a and 8b illustrate another embodiment of the perforated cylinder 8 that may be used instead of that shown in FIG. 7. That shown in FIG. 8a is exactly identical to the perforated cylinder 8 shown in FIG. 7, except that a saw tooth wire 81 is provided around its periphery; while that of FIG. 8b is provided with both a suction compartment 9 and an air discharge compartment 82 inside the perforated cylinder 8, and by installing the perforated cylinder 8 to the carding machine of FIG. 7 so that the opening 83 of the air discharge compartment 82 faces the carding cylinder 4 the transfer of the spinnable fibers deposited on the perforated cylinder 8 to the carding cylinder 4 is carried out in a much smoother manner.

The use of this perforated cylinder 8 shown in FIGS. 8a and 8b moreover is not limited in its use with the embodiment shown in FIG. 7 but can be installed in any of the other embodiments described herein.

The embodiment illustrated in FIG. 9 is of identical construction as the carding machine described with reference to FIG. 7, except that instead of the mote-knife the tip of the under casing 71 is bent back for purpose of reinforcement, and that the under casing 90 of the perforated cylinder 8 which at its tip has a sliding plate 92 attached slidably thereto is hinged at its base 91 and projects somewhat in an upward direction.

Thus, in the carding machine shown in FIG. 9, as it is possible to adjust the length of the sliding plate 92, the angle of deflection of the air stream forward of the sliding plate 92 can be controlled. As for the other functions, they are substantially the same as that of the carding machine shown in FIG. 7.

In the embodiment illustrated in FIG. 10 there is interposed between the licker-in 3 and the carding cylinder 4 a second licker-in 100. The undersides of the licker-in 3 and the second licker-in 100 are covered with an under casing 71. And from a certain point on this under casing 71 there extends a cowl 101 that covers the top of the perforated cylinder 8. At the fore part of the under casing 102 of the perforated cylinder 8 there is provided as to be slidable a sliding plate 104 similar to the sliding plate 62 shown in FIG. 6. And to the lower part 104b of the sliding plate 104 is attached an elastic sheet 105 that extends downwards as to contact the floor of the air chamber 6. Thus the rear wall of the air chamber 6 is constituted by means of the lower part 104b of the sliding plate 104 and the elastic sheet 105. Again, as the under casing 102 is hinged at its base 103, it is rotatable. Also, while not shown in the drawings, to the lower part 104b of the sliding plate 104 a mechanism for raising or lowering it is attached as in FIG. 6, and similarly a stud with a winged nut as in the same figure is provided at where the upper part 104a of said sliding plate 104 is fitted slidably with the under casing 102.

Therefore, in the carding machine illustrated in FIG. 10, a duct 106 is formed leading towards the opening of the perforated cylinder 8 by means of the cowl 101, the under casing 102 and the upper part 104a of the sliding plate 104. And, by adjusting the rotated position of the under casing 102 and the length of the upper part 104a of the sliding plate 104 the size of the opening 107 of the duct 106 is controlled, thereby controlling the intensity of

the air stream as well as its angle of deflection forward of the projecting tip 104c at the opening 107 of the duct 106.

While the invention has been described with reference to several of its principal embodiments, it will be apparent to a person skilled in the art that many changes and modifications are possible. However, it is to be understood that it is intended to cover all such changes and modifications so long as they do not depart from the scope of the invention as defined in the appended claims.

Having thus described the invention, what is claimed is:

1. A carding machine comprising a feed table and a feed roller disposed thereabove for feeding the material fibers, at least one licker-in provided adjacent said feed table, a carding cylinder disposed on the side of said licker-in opposite from said feed table with its periphery adjacent the periphery of the licker-in, an upper casing covering the upper part of said licker-in and a part of the upper part of the adjacently disposed carding cylinder, an air chamber enclosed with four walls provided below said licker-in, said air chamber being provided with an opening for the inflow of air in its wall nearest to the feed table, a perforated cylinder disposed below the carding cylinder at a point nearer to the licker-in, said perforated cylinder rotating in contiguity to said carding cylinder but being spaced at a definite interval from and out of engaging contact with said licker-in, said perforated cylinder having within it a suction compartment, said suction compartment opening at least at a point other than where said perforated cylinder and said carding cylinder come adjacent to each other, and the position of said perforated cylinder relative to said air chamber being such that said suction compartment within the perforated cylinder can draw the air contained in the air chamber.

2. The carding machine as defined in claim 1 in which the underside of said carding cylinder except the portion nearer to the perforated cylinder is covered with an under casing.

3. The carding machine as defined in claim 1 in which that part of the outer periphery of the perforated cylinder opposite that part where said suction compartment opens faces said air chamber directly.

4. The carding machine as defined in claim 3 in which a mote-knife is disposed below the licker-in spaced therefrom with at least an interval sufficient for passage of the fibers.

5. The carding machine as defined in claim 1 in which at least a part of the underside of said licker-in nearer to said carding cylinder is covered with an under casing having an opening, said opening communicating with a duct the other end of which opens towards the periphery of said perforated cylinder and said suction compartment within said perforated cylinder being directed to open vis-a-vis said duct opening at the end nearer to the perforated cylinder.

6. The carding machine as defined in claim 1 in which at least a part of the underside of the licker-in nearer to the carding cylinder is covered with an under casing spaced from said licker-in with an interval sufficient for the passage of the fibers deposited on the periphery of said licker-in.

7. The carding cylinder as defined in claim 6 in which the underside of the licker-in from the part close to the mote-knife to the part close to the carding cylinder is covered with a continuous under casing.

8. The carding machine as defined in claim 1 in which the periphery of the perforated cylinder is clothed with a saw tooth wire.

9. The carding machine, as defined in claim 1, in which the underside of the perforated cylinder is covered with an under casing positioned to be spaced from the underside of the perforated cylinder, and one end of the under casing is projected into said air chamber.

10. The carding machine as defined in claim 9 in which said third-named under casing is hinged at its base.

11. The carding machine as defined in claim 9 in which a sliding plate is provided as to be slidable at the forward portion of said third-named under casing.
